CARRYING CASE

Donald E. Leman, Glen Ellyn, Ill., assignor to Sunbeam Corporation, Chicago, Ill., a corporation of Illinois

Filed Dec. 9, 1963, Ser. No. 77,744

Term of patent 14 years

(Cl. D87—5)

FIG. 1 is a front elevational view of a carrying case showing my new design, the rear being substantially a mirror image thereof;

FIG. 2 is a side elevational view thereof, the opposite side being a mirror image thereof;

FIG. 3 is a top plan view thereof; and

FIG. 4 is a bottom plan view thereof.

The characteristic feature of my design resides in the combination on the carrying case disclosed of the particular floral embossed central panel extending completely around the case as shown.

I claim:

The ornamental design for a carrying case, as shown and described.
